UNITED STATES PATENT OFFICE.

HARRY E. WOERNLE, OF PITTSBURGH, PENNSYLVANIA, ASSIGNOR TO MCKINNEY MANUFACTURING COMPANY, OF PITTSBURGH, PENNSYLVANIA, A CORPORATION OF PENNSYLVANIA.

METHOD OF MAKING CHAIN BOLTS.

Application filed March 10, 1923. Serial No. 624,155.

To all whom it may concern:

Be it known that I, HARRY E. WOERNLE, a citizen of the United States, and resident of Pittsburgh, in the county of Allegheny and State of Pennsylvania, have invented a new and useful Improvement in Methods of Making Chain Bolts; and I do hereby declare the following to be a full, clear, and exact description thereof.

10 My invention relates to bolts, and more particularly to a method of making chain-bolts such as are withdrawn by pulling on a chain, a spring being provided to return the bolt to normal position.

15 The object of my invention is to form a bolt of this character from a single piece of wrought metal which is strong and durable, and which, by the simplicity of its manufacture, enables it to be produced at a minimum cost.

In the accompanying drawing, Fig. 1 is a side elevation of my improved bolt, the bolt proper and the spring being shown in dotted lines; Fig. 2 is a front view partly 25 in section; Fig. 3 is a front view of the bolt removed; Fig. 4 is a side view; Fig. 5 is a rear view; Fig. 6 is a bottom plan view of the bolt casing; and Figs. 7 and 8 are plan and edge views, respectively, of the blank 30 from which the bolt proper is formed.

The blank 2, which may be formed from a sheet of steel or other suitable metal, has the enlarged top-portion 3 and the shank-portion 4 extending down therefrom.

35 The bolt is formed from this blank by bending the upper portion 3 by means of suitable tools to form the upper tubular portion 5 of the bolt, while the shank-portion 4, for a portion of its length, is bent around to 40 form the semi-circular portion 6 with the shoulder 7 at the point where said portions meet.

Below the semi-circular portion 6 the shank-portion 4 of the blank is bent to form 45 the flat or angular portion 8, a shoulder 9 being consequently formed between said flat-portion 8 and the semi-circular portion 6.

The upper end of the blank 2 is convex, as at 10, and when the metal is bent to form 50 the upper tubular portion 5 the upper end of the bolt is formed with the customary rounded or beveled portion 12.

The bolt so formed is inserted in the customary casing 13, which is provided at its

lower end with the slot 14 to receive the 55 flattened lower portion 8 of the bolt. The spring 15 is interposed between the shoulder 7 and the lower end 16 of the casing, said spring having the tendency to hold the bolt in locked position. 60

A clevis 17 is secured to the lower end of the flat portion 8 which projects through the opening 14, and said clevis is connected to said flat portion by the split pin 18. A chain 19 is connected to the clevis 17. The 65 clevis 17 forms a stop which controls the upward movement of the bolt.

It will be apparent that the bolt may be readily reversed by withdrawing the flat portion 8 from the opening 14 and turning 70 the same, and then reinserting said flat portion in said opening.

By my invention I provide a chain-bolt which is light in weight, and yet has sufficient rigidity and strength to stand the 75 wear and tear to which it is subjected, while at the same time by being made of one piece of wrought-metal the simplicity of manufacture makes it possible to form the bolt quickly and at the same time at minimum 80 cost.

What I claim is:

1. The method of forming bolts which comprises providing a substantially flat blank having a wide upper portion whose 85 uppermost edge is of substantially arcuate form, bending said portion to bring the side edges thereof into adjacent position to form a tubular body portion, bending a portion of the blank to semi-circular form 90 of less diameter than said body portion, and forming a shank portion below said intermediate portion of angular form in cross section.

2. The method of forming bolts which 95 comprises providing a substantially flat blank having a wide upper portion, bending said portion to bring the side edges thereof into adjacent position to form a tubular body portion, bending a portion of the blank 100 to semi-circular form of less diameter than said body portion, and forming a shank portion below said intermediate portion of angular form in cross section.

In testimony whereof I, the said HARRY 105 E. WOERNLE, have hereunto set my hand.

HARRY E. WOERNLE.
